EXHAUST STEAM INJECTOR

Emanuel Rawson, North Bergen, N. J., assignor
to The Superheater Company, New York, N. Y.

Application May 7, 1932, Serial No. 609,858

9 Claims. (Cl. 103—265)

The present invention relates to exhaust steam injectors and has particular reference to exhaust steam injectors for supplying feed water to locomotive boilers. Still more particularly the invention relates to exhaust steam injectors of the type adapted to be operated wholly by live steam when exhaust steam is not available.

In the employment of exhaust steam injectors for supplying feed water to locomotive boilers, numerous widely varying conditions of locomotive operation must be taken into consideration if the injector is to operate satisfactorily, that is, is to be able to supply feed water to the boiler at all times, regardless of momentary locomotive operating conditions. In order to provide for continuous injector operation under the conditions existing in locomotive operation, numerous control systems have been heretofore proposed but the systems heretofore proposed have uniformly been based upon the utilization of steam admitted to the engine cylinders or exhaust steam from the locomotive engine as the means for actuating the control system.

In accordance with the present invention I propose to dispense with either exhaust or live steam as the means for controlling operation of the injector and instead employ electrical means responsive to the speed of operation of the locomotive engine for governing the injector control system. By this means I obtain numerous advantages as compared with prior control systems which will be more fully pointed out in connection with the ensuing description of a suitable form of apparatus for carrying the invention into effect.

In the drawing accompanying this specification and forming a part hereof:

Fig. 1 is a diagrammatic elevation of the fire box end of a locomotive boiler showing an injector arrangement embodying the present invention installed thereon;

Fig. 2 is a section on an enlarged scale of a part of the apparatus shown in Fig. 1;

Fig. 3 is an elevation on an enlarged scale of a part of the apparatus shown in Fig. 1; and

Fig. 4 is a similar view of another part of the apparatus shown in Fig. 1.

Turning now to the drawing, the fire box end of the locomotive boiler and the cab of the locomotive are indicated in dash lines A and the injector is indicated generally at B.

The injector indicated is of the general type disclosed in United States Patent No. 1,531,004 granted March 24, 1925 on the application of Malcolm Hard and William Buckbee, although it is to

be understood that the present invention is not limited in its application to this specific type of exhaust steam injector. It may be applied to other types of exhaust steam injectors as well.

A common characteristic of exhaust steam injectors of the type disclosed in the aforementioned patent and in similar types is the supply to the injector, in addition to water, of high pressure live steam, hereafter referred to as supplementary steam, and further, exhaust steam from the engine or when exhaust steam is not available, low pressure live steam. The low pressure live steam will hereafter be referred to as auxiliary steam.

In the injector arrangement illustrated, exhaust steam is admitted to the injector B through the conduit 10 leading from the engine exhaust pipe (not shown). Water is supplied to the injector through conduit 11 and the boiler feed water is delivered under pressure from the injector through the delivery conduit 12 which is connected to the usual boiler check valve (not shown). The injector overflow pipe is indicated at 13.

Steam for operating the injector is taken from the boiler turret indicated at 14 and is conducted to the injector through the high pressure steam supply pipe 15 in which is located the manually operable main control valve 16, ordinarily situated in the engine cab.

Pipe 15 is divided at the injector into two branches 16 and 17. Branch 16 supplies supplementary live steam at high pressure to a suitable nozzle in the injector and branch 17 supplies auxiliary live steam to the injector at low pressure to take the place of exhaust steam when the latter is not available.

The admission of auxiliary live steam to the injector is controlled through the medium of an automatic or changeover valve indicated generally at C, this valve operating to either open or close the branch 17. The use of automatic or changeover valves in control systems of the character in question is known per se and injectors of the character described ordinarily include exhaust steam control valves which operate in conjunction with the automatic or changeover valves so that either exhaust steam or auxiliary live steam is supplied to the injector.

The general construction and operation of apparatus of this type forms per se no part of the present invention and need not be described in detail.

For reasons which will appear hereinafter I prefer to employ an automatic or changeover valve of the type disclosed in the copending ap-

5 application of Malcolm Hard, Serial No. 323,852 filed December 5, 1928, and have illustrated a valve of this type in Fig. 2 which will now be briefly described. The valve comprises a casing 18 providing a chamber 19 in communication with the steam conduit 15 through a small orifice or choke port 20 and also in communication with the branch 17. The automatic or changeover valve 21 is located in chamber 19 and is provided 10 with a double seated head portion 21a and a piston portion 21b, the latter sliding in a suitable bore in the casing 18. A chamber 22 is formed in the casing above the valve 21 and a spring 23 may advantageously be employed to seat valve 21 15 against its lower valve seat. Above chamber 22 a second chamber 24 is provided in which is located a piston 25. Piston 25 is connected to a double seated relay valve 26 located in a third chamber 27. High pressure live steam is admitted through 20 passage 28 to the space above piston 25, and through a suitable clearance space 29 and channel 30 to chamber 22, when the relay 26 is in its upper position as shown in the figure. Chamber 24 is placed in communication with the live steam 25 supply admitted through passage 28, by means of a suitable port which may be in the piston as indicated at 31.

When the relay valve 26 is seated against its 30 lower seat, communication is established between the channel 30 and an atmospheric vent 32.

Chamber 22 is provided with a connection 33 leading to suitable means for actuating the valve controlling the admission of exhaust steam to the injector.

35 Chamber 24 is provided with a vent pipe 34 leading to atmosphere or, as indicated in Fig. 1, a zone of low pressure within the injector. A valve 35 is located in vent pipe 34 for controlling steam flow therethrough.

40 The operation of the changeover valve is as follows:

Assuming valve 35 to be closed as shown in Fig. 2 and the main control valve 16 to be open, high pressure live steam enters chamber 24 by way of passage 28 and port 31, causing piston 25 to lift the relay valve 26 to the position shown in the figure. With the relay valve in this position, high pressure steam passes through clearance space 29 and channel 30 to chamber 22 and holds 50 the changeover valve 21 against its lower seat, thus closing the branch 17 and preventing the admission of auxiliary live steam to the injector. High pressure live steam from chamber 22 passes through the connection 33 to open the exhaust 55 steam valve so as to admit exhaust steam to the injector.

If valve 35 is open, chamber 24 is vented through pipe 34 and the release of pressure from this chamber forces piston 25 down so as to seat 60 relay valve 26 against its lower seat. This closes communication between channel 30 and the passage 28 through which high pressure operating steam is admitted to the valve and establishes communication between channel 30 and the atmospheric vent 32. Consequently, pressure in chamber 22 is released to atmosphere and valve 21 is lifted from its seat by unbalanced steam pressure in chamber 19. At the same time the release of pressure in chamber 22 permits the 65 exhaust steam valve to close due to release of pressure in connection 33.

70 As soon as steam starts to flow through branch 17 after valve 21 is lifted, the pressure of this steam is automatically reduced due to the throttling action of the choke port 20.

From the foregoing description it will be evident that for proper control of the injector, valve 35 should be closed only when exhaust steam from the engine is available in suitable quantity and at suitable pressure for proper injector operation and that at all other times valve 35 should be open so as to permit the injector to be operated as a live steam injector through the medium of the use of auxiliary steam.

5 75 In accordance with the present invention I provide for electrical speed responsive control of valve 35, and to this end the valve head 35' of valve 35 is connected by means of a suitable stem 36 to the core 37 of a solenoid the coil of which is indicated at 38. The valve head 35' is moved to 10 open position by spring 39 acting on stem 36. As will be evident from Fig. 2 valve 35 will be closed 15 when the solenoid coil 38 is energized and will open when the coil is de-energized. For the purpose of controlling energization of the solenoid 20 coil 38 I provide electric current generating means such as a generator indicated at 40 in Fig. 1. Generator 40 is operated at a speed varying in accordance with the speed of operation of the locomotive engine and may advantageously be 25 driven by means of a belt 41 from one of the axles 42 of the locomotive.

30 Preferably, generator 40 is of the type generating current the voltage or amperage of which varies in accordance with variations in speed 30 of the generator. One terminal of the generator is connected to the solenoid coil 38 by means of the connection 43 and the other terminal of the generator is connected to the solenoid coil by means of connections 44 and 45. Electrical connection between connections 44 and 45 is controlled by means of a device indicative of steam admission to the locomotive engine. Preferably, some part of the throttle control mechanism for the main engine is employed for this purpose and 40 a suitable arrangement has been indicated in Figs. 1 and 3. In accordance with the arrangement shown, the usual pivoted throttle lever 46, having connected thereto the throttle operating rod 47, is provided with a spring contact 48 insulated by suitable strip of insulating material 48' and having connected thereto the connection 44. The quadrant 49 has attached thereto a metal contact strip 50 against which the spring contact 48 is adapted to bear. The strip 50 is 50 advantageously insulated from the quadrant 49 by means of the strip of insulating material 51. Contact strip 50 has connected thereto the connection 45, and the portion of the strip at and adjacent to the position of lever 47 corresponding 55 to closed throttle is covered by a strip of insulating material 52, the position of which on the contact strip 50 may be altered by means of the adjusting screw 53.

With the above described arrangement it will 60 be seen that the generator 40 and the solenoid coil 38 are connected in an electric circuit which will be broken when the throttle lever 47 is in closed position or in a position adjacent thereto and which will be completed when the throttle 65 lever is moved to a position admitting steam in predetermined quantities to the engine. It will further be evident that when the engine is standing still or is operating below a predetermined speed, the solenoid coil 38 will not be energized 70 even if the engine throttle is open and contact is made at contact 48, due to the fact that with the engine standing still or moving at a speed below a predetermined rate the generator 40 will not produce current of sufficient strength to energize 75

size coil 38 and close valve 35 against the pressure of spring 39. It follows therefore that with the arrangement illustrated, the solenoid valve 38 will be energized so as to cause the auxiliary steam supply to be shut off from the injector only after a certain speed of operation of the engine has been obtained and also only after the engine throttle has been opened by a predetermined amount. With the control circuit operating in response to these two factors, assurance is had that the auxiliary steam supply will be cut off and exhaust steam admitted to the injector only under operating conditions which ensure a proper exhaust steam supply. By way of illustration let us consider conditions when the locomotive is drifting. Under these conditions the speed responsive generator may be producing current of sufficient strength to energize the solenoid coil, but when the engine is drifting the throttle must be adjacent closed position, in which event the control circuit is broken due to the fact that the contact 48 is on the insulating strip 52. Under drifting conditions not enough steam is supplied to the engine to provide sufficient exhaust steam for injector operation and as explained above, under these conditions the control circuit is broken at the throttle and auxiliary steam is admitted to the injector.

Under some conditions trains are held stationary on grades by admitting just sufficient steam to the engine to prevent backward movement of the locomotive. Under such conditions the throttle may be opened sufficiently to close the control circuit, but, due to the lack of movement of the locomotive no current is available in the circuit for energizing the solenoid. Under the above conditions there is obviously no exhaust steam available for injector operation even though the engine throttle is open and under these conditions the control system provides for the admission of auxiliary live steam to operate the injector.

With a control system according to the present invention, numerous advantages are obtainable. In systems heretofore employed where engine steam chest pressure is employed to govern the position of the changeover valve, the above described condition of operation, in which steam is admitted to the engine without producing exhaust steam available for injector operation, leads to serious operating difficulties which can only be corrected by the addition of more or less complex auxiliary control means. In systems where in exhaust steam pressure is employed as an actuating medium for the changeover valve difficulties are encountered due to pulsations or variations in exhaust steam pressure which are difficult to eliminate with practical equipment and without undue complication. Unless such pulsations are effectively eliminated or neutralized, the control equipment operated by exhaust steam pressure is subject to chattering operation when the exhaust steam pressure is at or about the correct pressure for causing changeover of the injector from exhaust steam operation to live steam operation or vice versa.

By the present arrangement all of the difficulties heretofore encountered are eliminated. The control equipment is extremely simple, all piping for conducting operating steam from the engine steam chests is eliminated as is also all piping for conducting exhaust steam to a diaphragm or other valve to be operated thereby. Furthermore, the entire control equipment may be built as a unit at the injector because of the fact that

no means, such as long pipes, needs to be used to provide the so-called timing chambers heretofore found necessary in exhaust steam operated control systems, timing chambers being resorted to in previous systems in order to eliminate as far as possible the chattering operation due to pressure pulsations in the exhaust steam supply.

Ordinarily in the operation of locomotives the position of the reverse lever for the main engine, which also serves to regulate the amount of engine cut-off of the engine, is indicative of engine speed, a long cut-off being employed at slow speeds under heavy load and the cut-off being shortened as the speed increases. This provides an additional means whereby a control circuit in accordance with the present invention may be further governed. As shown in Fig. 4, the reverse lever 54 is provided with a contact 55 insulated from the lever by the strip 56 and the quadrant 57 is provided with a contact strip 58 insulated from the quadrant by strip 59. An insulating strip 60 provides for breaking contact between parts 55 and 58 when the reverse lever is in mid position or adjacent thereto.

It is possible to employ the reverse lever instead of the throttle lever as the means indicative of steam admission to the engine but the throttle lever arrangement is to be preferred. If the reverse lever is employed as a factor controlling the electric circuit, I prefer to connect the contacts governed by this lever in series with the contacts governed by the throttle lever so that operation of the injector on exhaust steam can be effected only if the throttle lever and the reverse lever are both in correct positions for admitting steam to the engine. Ordinarily the engine throttle will never be opened sufficiently to make contact in the circuit unless the reverse lever is in a position such that the valve gear will admit a suitable quantity of steam to the engine but it is possible for the engine throttle to be opened and for steam to be substantially shut off from the engine because of the fact that the engine valve gear is in neutral position or in a position giving an extremely short cut-off. The possibility of shifting the injector to exhaust steam operation under the above unusual circumstances may be effectively guarded against by providing circuit contacts at both the throttle mechanism and the reverse lever mechanism.

It will be apparent from the foregoing description that many variations in the arrangement shown by way of illustration may occur to those skilled in the art without departing from the scope of the invention. Thus for example a type of changeover valve other than that illustrated may be employed. For example, a valve of the type disclosed in United States Patent No. 1,574,798 granted to Hans Deutsch on March 2, 1926, may be employed. However, it is preferable to use a valve of the type illustrated since it has been found that through the medium of a relay valve the size of the solenoid and consequently of the generator necessary to effect the desired control, may be very materially reduced. It will also be evident that generators of various different types may be employed, but a generator producing electrical energy the value of which varies with the speed of operation of the generator is to be preferred because of the relative simplicity as compared with other electrical arrangements involving circuit closing and opening means which are speed responsive.

For purposes of the present invention the electric circuit comprising the solenoid is to be

considered as being energized only when it is energized to the degree necessary to effect actuation of the valve operated by the solenoid. It will be apparent that if a generator is placed 5 directly in the circuit, some current will flow through the circuit, provided the circuit is closed, at engine speeds below that speed at which the change-over valve should be shifted to the position cutting off the auxiliary steam supply, but 10 until the amount of energy developed in the circuit reaches a value sufficient to effect actuation of the solenoid operated valve, the circuit is to be considered as de-energized.

While for purposes of illustration the invention 15 has been shown as applied to an injector delivering water at high pressure to a locomotive boiler, and consequently requiring a supply of supplementary high pressure steam, the invention is not limited to this type of injector but 20 may be employed equally well in conjunction with injectors operating with lower delivery pressures and not requiring high pressure steam.

What is claimed is:

1. Apparatus of the character described comprising mechanism for governing steam admission to an engine, an exhaust steam injector adapted to operate on steam exhausted from said engine and a control system for said injector comprising a changeover valve for admitting auxiliary live steam to the injector and means comprising an electric circuit for governing actuation of said changeover valve, said circuit including means responsive to variations in engine speed for energizing the circuit when the engine speed reaches a predetermined value and means associated with said mechanism for opening the circuit when said mechanism is adjusted for steam admission to the engine at a rate below a predetermined value, said changeover valve being closed when said circuit is energized and being opened when the circuit is de-energized.

2. Apparatus of the character described comprising throttle mechanism for governing steam admission to an engine, an exhaust steam injector adapted to operate on exhaust steam from said engine and a control system for said injector comprising a changeover valve for admitting auxiliary live steam to the injector and electrical means for governing operation of said changeover valve comprising an electric circuit including a generator adapted to energize the circuit when the speed of the engine reaches a predetermined value and contacts adapted to open the circuit when the throttle mechanism is in closed position.

3. Apparatus of the character described comprising throttle mechanism for governing steam admission to an engine, an exhaust steam injector adapted to operate on exhaust steam from said engine and a control system for said injector comprising a changeover valve for admitting auxiliary live steam to the injector, a solenoid operated valve for effecting closure of the changeover valve upon energization of the solenoid, and means for energizing and de-energizing said solenoid comprising an electric circuit including a generator operable at a speed varying with variations in engine speed and contacts operable to break the circuit upon movement of said throttle mechanism to closed position.

4. In an exhaust steam injector of the type adapted to operate on exhaust steam from an engine equipped with a throttle mechanism controlling the steam flow to the engine, a control system comprising a fluid pressure operated

changeover valve for admitting live steam to the injector, a fluid pressure operated relay valve for governing the position of said changeover valve, said relay having a vent and being movable upon closure of said vent to a position causing closure of the changeover valve, an electric solenoid operated valve for closing said vent upon a predetermined degree of energization of the solenoid, a generator operable at speed varying with the engine speed for energizing said solenoid, and means associated with the throttle mechanism to prevent the energization of the solenoid unless the throttle is open at least to a predetermined extent.

5. In an exhaust steam injector of the type 15 adapted to operate on exhaust steam from an engine equipped with a throttle mechanism controlling the steam flow to the engine and with a cut-off mechanism determining the point of cut-off, a control system comprising a fluid pressure operated changeover valve for admitting live steam to the injector, a fluid pressure operated relay valve for governing the position of said changeover valve, said relay having a vent and being movable upon closure of said vent to a 25 position causing closure of the changeover valve, an electric solenoid operated valve for closing said vent upon a predetermined degree of energization of the solenoid, a generator operable at speed varying with the engine speed for energizing said solenoid, means associated with the throttle mechanism to prevent the energization of the solenoid unless the throttle is open at least to a predetermined extent, and means associated with the cut-off mechanism to prevent the energization of the solenoid below a predetermined length of cut-off.

6. In an exhaust steam injector of the type adapted to operate on exhaust steam from an engine, a control system comprising a changeover 40 valve for admitting auxiliary live steam to the injector, electrically energized means for causing said valve to be closed and means responsive to variations in the speed of the engine and to variations in admission of steam to the engine for 45 actuating said electrically energized means to cause said valve to be closed only when the speed of the engine exceeds a predetermined value and steam is admitted to the engine in excess of a predetermined rate.

7. In an exhaust steam injector of the type adapted to operate on exhaust steam from an engine, a control system comprising a changeover valve for admitting auxiliary live steam to the injector, means for governing actuation of 55 said valve comprising an electric circuit adapted to be energized to cause said valve to be closed, and means associated with said circuit for causing it to be energized only when the speed of the engine exceeds a predetermined value and steam 60 is admitted to the engine in excess of a predetermined rate.

8. That improvement in the operation of a control system for exhaust steam injectors having a changeover valve for admitting auxiliary live 65 steam to the injector which comprises generating an electric current having characteristics varying in accordance with variations in the speed of the engine from which exhaust steam is supplied to the injector and utilizing the variations 70 in said characteristics to effect closure of the changeover valve only when the engine exceeds a predetermined speed and steam is admitted to the engine at a rate in excess of a predetermined value.

9. In an exhaust steam injector of the type adapted to operate on exhaust steam from an engine, a control system comprising a changeover valve for admitting auxiliary live steam to the injector and means for governing the actuation of said valve comprising an electric circuit having an electrical characteristic alterable from a first condition causing said valve to open to a second position causing said valve to close, said circuit including means responsive to variations in admission of steam to said engine and means responsive to variations in engine speed for producing and maintaining said second condition only when steam admission to the engine and speed of the engine exceed predetermined values.

EMANUEL RAWSON.
